UNITED STATES PATENT OFFICE.

FRED SWALLOW AND HENRY YUST, OF SENECA, MISSOURI; SAID SWALLOW
ASSIGNOR TO SAID YUST.

FLOUR-SIFTER.

SPECIFICATION forming part of Letters Patent No. 460,493, dated September 29, 1891.

Application filed April 18, 1891. Serial No 389,497. (No model.)

To all whom it may concern:

Be it known that we, FRED SWALLOW and HENRY YUST, citizens of the United States, residing at Seneca, in the county of Newton 5 and State of Missouri, have invented certain new and useful Improvements in Flour-Sifters; and we do hereby declare the following to be a full, clear, and exact description of the invention, such as will enable others skilled 10 in the art to which it appertains to make and use the same.

Our invention consists in new and useful improvements in flour-sifters, which will be hereinafter fully described and claimed.

15 Referring to the accompanying drawings, Figure 1 is a perspective view of our new and improved flour-sifter. Fig. 2 is a vertical sectional view taken through the sifter. Fig. 3 illustrates in detail the operating gearing and 20 connections.

The same numerals of reference indicate corresponding parts in the several figures.

Referring to the several parts by their designating-numerals, 1 indicates the cylindrical 25 body of our new and improved sifter, near the lower end of which is secured on its inner side the slightly-inclined flange 2. Just below the flange 2 an annular groove 3 is pressed or formed in the body 1. In the lower end of 30 the body is mounted the reciprocating sieve, which is formed of wire-cloth, the edges of which are secured to a metal guide-rim 5, the outer edge of which fits and plays in the annular groove 3, formed in the lower end of the 35 body 1. On the side of the cylindrical body is secured a bearing 6, on which is pivoted the large cog-wheel 7, having the small handle 7^a for convenience in revolving it. On the lower part of the bearing 6 is pivoted a 40 cog-pinion 8, which is formed with the projecting wrist-pin 8^a.

9 indicates a connecting rod or wire, one end of which is pivotally mounted on the wrist-pin 8^a of the cog-pinion, while its other 45 end is pivotally connected to the outer end of an arm 10, projecting out from the sieve through a slot 11 in the lower end of the body 1. It will now be seen that as the cog-wheel 7 is revolved by its handle the cog-pin- 50 ion will be given a large number of revolutions for each single revolution of the drive-

wheel 7, and as the pinion is thus revolved it will, through the connecting-rod 9 and arm 10, rapidly reciprocate or shake the movable sieve in the lower end of the body, thus effectively sifting the flour with a motion which closely resembles that given by hand to the ordinary flour-sifter. A series of spurs or upwardly-reaching arms 12 are erected upon the upper surface of the sieve and are adapted to move and thoroughly agitate the contents of the sifter and thus produce better results, as will be readily understood.

It will be seen that our improved flour-sifter dispenses with the rotating agitator 65 commonly used, which by rubbing over the surface of wire-cloth tends to rub dirt and hard lumps of flour through the sifter and wears out the wire-cloth.

Our invention, while sifting flour very rapidly, retains all dirt and hard lumps of flour and reciprocates the sieve back and forth with great rapidity, instead of revolving an agitator over a fixed sieve-cloth, as in some of the flour-sifters of this class.

75 From the foregoing description, taken in connection with the accompanying drawings, the construction, operation, and practical advantages of our new and improved flour-sifter will be readily understood without requiring further description.

Having thus described our invention, what we claim, and desire to secure by Letters Patent, is—

The combination of the body 1, formed near 85 its lower end with the annular retaining and bearing groove 3, the wire sieve 4, provided with the series of upwardly-projecting spurs 12 and having the metal guide-rim 5, movably fitting in said groove 3, and the projecting arm 10, the drive-wheel 7, the pinion 8, having the projecting wrist-pin 8^a, and the connecting-rod 9, pivotally connected to said wrist-pin and to the outer end of the arm 10, substantially as set forth.

95 In testimony whereof we affix our signatures in presence of two witnesses.

FRED SWALLOW.
HENRY YUST.
